UNITED STATES PATENT OFFICE

2,063,120

STORE FRONT CONSTRUCTION

Francis J. Plym, Niles, Mich., assignor to The Kawneer Company, Niles, Mich., a corporation of Michigan

Application June 24, 1935, Serial No. 28,082

8 Claims. (Cl. 20—56.4)

This invention relates to store front construction and more particularly to novel means for mounting and holding the glass in position.

Among the objects of my invention is to provide novel means for resiliently but firmly holding the glass in position in the store front.

Another object is to provide a resilient bar or strip capable of being forced against the inside edge of the glass to resiliently hold the same against the rigid outer stop.

A further object is to provide means for holding the glass in position, which means is adjustable from the inside of the window instead of the outside.

A still further object is the provision of a rigid front and adjustable back in store front construction.

Another object is means for causing the edges of the glass to meet in a novel manner at the corner of the store front construction and without the necessity of interposing special joint members or the like at such corner.

A still further object is the provision of store front construction which adapts itself to different parts of the same being made in different colors if desired.

A further object is the provision of store front construction in which the light for illuminating the interior of a show window will be below the line of vision of anyone looking through the show window.

Another object is the provision of means for clamping glass in position in store front construction from the inside and capable of fine adjustment to produce the proper degree of pressure against the pane of glass to yieldingly hold it in proper position.

Other objects, advantages and capabilities will later more fully appear.

My invention further resides in the combination, construction and arrangement of parts illustrated in the accompanying drawings, and while I have shown therein a preferred embodiment I wish it understood that the same is susceptible of modification and change without departing from the spirit of my invention.

In the drawing:—

Fig. 1 is a fragmentary perspective view of the outside of my improved store front construction showing a corner.

Fig. 2 is a fragmentary vertical transverse section at a greater or less distance away from the meeting edges of the two pieces of glass at the corner.

Fig. 3 is a horizontal transverse cross-section taken on the line 3—3 of Fig. 2.

Referring more in detail to the drawing, my improved store front construction is mounted upon a foundational member or sill block 1 of greater or less height, on the inside of which and near the bottom portion is provided one or more electric lights 2 connected to a suitable source of electricity for illuminating the interior of the show window without the electric light bulb being visible or too conspicuous from the outside of the show window. This electric light is hidden from view from the exterior of the show window by reason of its being mounted close up to the foundational member 1 and in the corner adjacent the bottom of the same. This light, if desired, may be provided with a reflecting member 3 in order to suitably reflect the light into the interior of the show window.

Mounted upon the upper surface of the foundational member 1 is the sash member S, which may be extruded or rolled from any suitable metal (preferably a metal that does not easily corrode). This sash member S is formed on its outer face with the outer moulding 4, which also serves as a protection against weather, dirt and the like. The outer moulding 4 merges into the downwardly extending channel portions 5 and 6, between which is formed the channel 7 adapted to snugly receive the stop member 8, which latter may or may not, as desired, be provided on its upper edge with the inwardly extending nose 9. If the inwardly extending nose 9 is not provided, any other suitable formation at the upper edge of the stop member that will function as a stop for the outside of the panes of glass a and b may be used.

Spaced inwardly from the sash member channel 7 and extending upwardly is the upstanding flange 10, through which at suitably spaced intervals is threadedly mounted the adjusting screws 11, each of which is provided with knurled adjusting heads 12. In order to provide greater stability for section S it is formed with a downwardly extending supporting flange 13, which rests upon the upper face of the foundational member 1, which is also true of the bottom portions of the channel forming members 5 and 6. As shown in the drawing, the members 4, 5, 6, 10 and 13 are integrally formed and, as stated above, this completed section may be either extruded or rolled as desired. The glass 14 is seated upon suitable cushioning blocks 15, which may be formed of wood, leather or any other material.

that will give a suitable cushioning effect to the glass.

Interposed between the upstanding flange 10 and the inner face of glass 14 are the back members or clamping members 16, which are preferably made of resilient material so formed that when pressed by means of the adjusting screw 11, between the end of the adjusting screw and the glass, will yieldingly hold the glass in place against stop 9. While I prefer the member 16 to be of resilient material, it is understood that a non-resilient material may be used, providing the pressure between it and the glass is adjusted accurately in order not to break the glass.

From the above it is seen that I have provided a novel mounting and clamping means for store front construction, and one in which the edges of the glass meet at the corners of the store front without the necessity of the interposition of special joining members, and yet present the glass corners in even, sightly appearance and so closely fitted as to keep out the weather, either with or without a protective strip being applied to the exterior of such store front corner. The proper registry or alignment of the edges of the glass in this corner construction is shown and readily understood in Fig. 3.

Having now described my invention, I claim:—

1. A store front construction, comprising a sash member having a stop member and a flange projecting from the inner face thereof, said stop member and flange being laterally spaced apart, the stop member being adapted to have a pane of glass pressed thereagainst, a resilient back member adjacent the flange, and adjustable means mounted on said flange and adapted to seat against said back member for forcing said back member into resilient contact with a pane of glass to grip the glass between the back member and the stop member.

2. In a store front construction, a sash member having a longitudinal channel formed therein and a longitudinal flange formed thereon, a longitudinal stop member snugly but removably seated in said channel and adapted to have pressed thereagainst a pane of glass seated on the adjacent face of the sash member, a back member positioned between the flange and stop member and adapted to bear against the pane of glass, and a plurality of adjusting screws mounted in said flange and bearing against said back member whereby upon rotation of said screws the glass will be gripped between the back member and stop member.

3. In a store front construction, a sash member having a longitudinal channel formed therein and a longitudinal flange formed thereon, a longitudinal stop member snugly but removably seated in said channel and adapted to have pressed thereagainst a pane of glass seated on the adjacent face of the sash member, a back member positioned between the flange and stop member and adapted to bear against the pane of glass, and a plurality of adjusting screws mounted in said flange and bearing against said back mem-

ber whereby upon rotation of said screws the glass will be gripped between the back member and stop member, said sash member having a supporting flange adjacent said first mentioned flange.

4. In a store front construction, a sash member integrally formed of suitable metal and having an outer moulding portion, a pair of adjacent but laterally spaced walls forming a channel therebetween, a seat for a pane of glass, an upstanding flange and a supporting flange, a separate stop member seated in said channel, means for clamping a pane of glass between the stop member and the upstanding flange, and means on said flange for adjusting said clamping means.

5. In a store front construction, a sash member integrally formed of suitable metal and having an outer moulding portion, a pair of adjacent but laterally spaced walls forming a channel therebetween, a seat for a pane of glass, an upstanding flange and a supporting flange, a separate stop member seated in said channel, and means for clamping a pane of glass between the stop member and the upstanding flange, said means comprising adjusting elements mounted in the upstanding flange and a resilient back member adapted to be forced against the pane of glass by said adjusting elements.

6. A sash member for a store front construction, said sash member being integrally formed of metal and having a pair of adjacent spaced apart wall members forming a channel adapted to receive a stop member, a projecting flange, a member adapted to seat against the pane of glass, and means on said projecting flange for forcing said last mentioned member into seating engagement with the glass.

7. In a store front construction, a pair of sash members meeting at an angle to form a corner, each of said sash members being formed of metal and having a channel and a projecting flange, a projecting stop member seated in the channel of each of said sash members, adjusting elements carried by the projecting flange of each of said sash members, and a clamping member associated with the adjusting elements of each of said sash members, whereby a pane of glass may be gripped between the stop member and the clamping member in each of said sash members with the vertical edges of the two panes of glass meeting at the corner in proper alinement and being substantially weather tight.

8. In a store front construction, a sash member having a rigid stop member along its outer edge adapted to have a pane of glass pressed outwardly thereagainst, a projecting flange along the inner edge of the sash member, adjusting elements mounted on said projecting flange, and a back member associated with said adjusting elements and adapted to force a pane of glass against the stop member whereby the pressure for gripping the pane of glass in position is adjustable from the inner side of the sash member.
